JOHN MARTINO AND JOHN CURRIE, OF PHILADELPHIA, PENNSYLVANIA,
ASSIGNORS TO CHARLES NOBLE & COMPANY, OF SAME PLACE.

Design No. 4,167, dated June 21, 1870; antedated May 26, 1870.

DESIGN FOR PLATES AND FEET OF THE "DEXTER" COOKING-STOVE.

The Schedule referred to in these Letters Patent and making part of the same.

We, JOHN MARTINO and JOHN CURRIE, both of Philadelphia, county of Philadelphia, State of Pennsylvania, have invented and produced a new and original Design for the Plates and Feet of the "Dexter" Cook-Stove, of which the following is a specification.

On reference to the accompanying drawings—

Figures 1 and 2 represent the front plates;

Figure 3, the side-plate; and

Figures 4 and 5, the feet of the stove.

The oven-door A, fire-door B, front doors C, and front plate F, of the stove, are all ornamented alike, the design consisting of a beading, e, composed of alternate round and oblong projections, within which is an oval panel, h, the latter containing an ornament, i, of the character clearly shown in the drawings.

The opposite ends of the front plate F are swelled or rounded, and on each is an ornament, k.

The opposite ends of the lower front plate and out-

wardly-projecting hearth are ornamented by a beading, l, and scrolls m.

The side-plate of the stove has an ornament, p, between the oven and fire-doors.

The feet of the stove are ornamented in the manner clearly shown in figs. 4 and 5.

We claim the design for the plates and feet of the "Dexter" cook-stove, substantially as described, and as represented in and by the accompanying drawings.

In testimony whereof we have signed our names to this specification in the presence of two subscribing witnesses.

JOHN MARTINO.
JOHN CURRIE.
